(57) **CLAIM**

The ornamental design for a two slot cruciform catheter section, as shown and described.

DESCRIPTION

FIG. 1 is a front elevational view of a two slot cruciform catheter section, an adjacent section of the catheter being shown in phantom, the rear elevational view being a mirror image thereof,

FIG. 2 is a right side elevational view thereof, the left side elevational view being identical thereto; and,

FIG. 3 is a top plan view thereof, the bottom plan view being identical thereto.

The phantom lines in the drawings indicate environmental structure which forms no part of the claimed design.
